UNITED STATES PATENT OFFICE.

CHRISTOPHER BRYANT, OF WORCESTER, MASSACHUSETTS.

IMPROVEMENT IN TABLES FOR MORTISING-MACHINES.

Specification forming part of Letters Patent No. 149,433, dated April 7, 1874; application filed March 7, 1874.

To all whom it may concern:

Be it known that I, CHRISTOPHER BRYANT, of the city and county of Worcester and Commonwealth of Massachusetts, have invented certain new and useful Improvements in Tables for Mortising-Machines for cutting window-jambs for the reception of their pulleys and pulley-plates; and I do hereby declare the following to be a full, clear, and exact description of the same, reference being had to the accompanying drawings, forming a part of this specification, and in which—

Figure 1 represents a top or plan view of said table. Fig. 2 represents a vertical central section on line A B, Fig. 1; and Fig. 3 represents a top or plan view of the table when used in a somewhat different manner from that shown in Figs. 1 and 2.

To enable those skilled in the art to which my invention belongs to make and use the same, I will proceed to describe it more in detail.

In the drawings, the part marked A represents the table of a common mortising-machine, and which table, it will be understood, is capable of being adjusted back and forward under the chisel. Upon the top of table A is placed the main part B of my improved table, having a stop-piece, *a*, fastened to the under side at one end, and an adjustable stop-piece, *b*, secured at the other end. Piece *b* is formed with two ear-pieces, 1 and 2, which fit to the edge of part B, and through the ear-piece 1 is passed a thumb-screw, *b'*, whereby said piece *b* can be set at a greater or less distance from the end of the part B. Upon the other end of the part B is secured a cross-piece, B', on its upper side. Upon the cross-piece B' is fastened the rear end of a spring holding-piece, C, the front end of which is provided with a thumb-piece, *c*, and a stop or holding piece, D, to fit the dado *e* in the end of the jamb E.

The operation is as follows: The operator places table B upon the mortising-machine table A, and then adjusts clamp-stop *b* to give the necessary longitudinal motion to table B for cutting the mortise, both for the pulley and cord, as well as that for the pulley-plate. One end of the jamb E for the window-casing is then placed upon table B, and if of that class having dadoes or notches *e*, the stop part D

of spring-piece C is allowed to enter the same, as shown in Fig. 2. The mortising-machine table is now adjusted to bring the jamb into the proper position as respects the chisel, when the table B, with the jamb thereon, is moved, while the chisel is in operation, from a central position, longitudinally, until stop *a* strikes against the end of table A, when the chisel is reversed, and table B is moved longitudinally in the other direction until stop *b* strikes the other end of table A, when the work is completed. If the jambs do not have the groove *e*, the stop-piece *d* is turned around for the jamb to abut against, as shown in Fig. 3, and stop-piece D rests upon the jamb, its point *f* entering the wood, and holding the jamb from slipping longitudinally out of place while the mortise is being cut. I prefer, in general practice, to have two spring-pieces, C, one having a point, *f'*, and the other none, since, when mortising those having the dadoes or notches *e*, the stop D entering said groove is sufficient without the point *f*.

By having two spring-pieces, C, one can be removed easily and the other substituted, as occasion may require. When not in use, the piece *d* can be turned out of the way under the spring-piece C, as shown in Fig. 1. It will be observed that both the table B and the jamb are pushed back against the back A' of the table A.

The invention above described is designed to be used more particularly in connection with an improved chisel for cutting the pulley and plate mortises at the same time, and for which improvement in chisels I have heretofore applied for Letters Patent.

It will be understood that mortising-table A, as well as my improved table above described, may be of any desired length, those shown in the drawings being sufficient to illustrate the principle and mode of operation of my said invention, which has been fully tested, and has been found to be of great practical value and importance, since an inexperienced workman, by the aid of one of my improved chisels and the above-described table, can cut the mortises with far greater accuracy and precision than the most skillful workman could perform the same operation as practiced previous to my said improvements, while at

the same time he can do about four or five times as much work in the same length of time. Previous to my said invention, the mortises had to be laid out, and they were cut by two different operations—that is, the mortise for the pulley-plate was not cut by the same operation which cut the mortise for the pulley and cord.

It will be noticed that the arrangement is such, that after the mortising-machine table A has been once adjusted laterally, no further adjustment is required, and all the operator has to do is to place the jambs E in position, as shown, and then move the table B back and forth as the work progresses, reversing the chisel at the proper time, so as to cut the mortise at both ends in the proper shape.

Having described my improved table for mortising or cutting window-jambs, what I claim therein as new and of my invention, and desire to secure by Letters Patent, is—

1. The combination, with the table part B, of stop-piece a, cross-piece B', and spring holding-piece C, provided with stop-piece D, substantially as and for the purpose set forth.

2. The combination, with the table part B, of stop-pin a, adjusting stop-piece b, stop-piece d, and spring holding-piece C, substantially as and for the purposes set forth.

CHRISTOPHER BRYANT.
